UNITED STATES PATENT OFFICE.

JOSEPH FRIEDMAN, OF BROOKLYN, NEW YORK.

DESIGN FOR A FRUIT BOWL OR SIMILAR ARTICLE.

Application filed June 8, 1922. Serial No. 2,587. Term of patent 14 years.

To all whom it may concern:

Be it known that I, JOSEPH FRIEDMAN, a citizen of the United States, and a resident of the city of New York, in the borough of Brooklyn and State of New York, have invented a new, original, and ornamental Design for a Fruit Bowl or Similar Article, of which the following is a specification, reference being had to the accompanying drawings, forming part thereof.

The figure is a perspective view of a fruit bowl or the like embodying my new design.

My invention comprehends the provision of a circumferential band or zone adjacent the top of the bowl having thereon ornamentation consisting of the representation in relief of pastoral scenes and living figures taken from the early Dutch period, and handles or ears having ornamentation similar to the ornamentation on the circumferential band.

I claim:

The ornamental design for a fruit bowl or similar article, as shown and described.

JOSEPH FRIEDMAN.
